Charles A. Baratelli, Cambridge, Thomas W. F. Chin, Chelsea, and Harold A. Marsh, Brookline, Mass., assignors to Polaroid Corporation, Cambridge, Mass., a corporation of Delaware

Application September 12, 1946, Serial No. 133,262

Term of patent 3½ years

(Cl. D14—6)

To all whom it may concern:

Be it known that we, Charles A. Baratelli, Thomas W. F. Chin, and Harold A. Marsh, citizens of the United States, residing, respectively, at 1737 Cambridge Street, Cambridge, in the county of Middlesex and State of Massachusetts, 475 Broadway, Chelsea, in the county of Suffolk and State of Massachusetts, and 571 Hammond Street, Brookline, in the county of Norfolk and State of Massachusetts, have invented a new, original, and ornamental Design for an Automotive Visor or Similar Article, of which the following is a specification, reference being had to the accompanying drawing, forming part thereof.

Figure 1 is a front elevational view of an automotive visor or similar article showing our new design; and

Fig. 2 is an end elevational view of the same in bent position.

We claim:

The ornamental design for an automotive visor or similar article, substantially as shown,

CHARLES A. BARATELLI.
THOMAS W. F. CHIN.
HAROLD A. MARSH.
